UNITED STATES PATENT OFFICE.

GEORGE A. GAUTHIER, OF DANBURY, CONNECTICUT.

OILING SYSTEM FOR FORD CARS.

Application filed June 28, 1923. Serial No. 648,207.

This invention relates to an oiling system for an automobile engine, and particularly to a device for conducting oil from the rear to the forward end of the motor casing or housing of a Ford engine.

In the usual installation of an engine of this type an oil conducting pipe leads from a position adjacent the rotating magnets of the magneto to the forward end of the crank case with a funnel to collect oil at a point adjacent this rotating element, but in this construction the oil is conducted by gravity from the inlet end to the forward end of the crank case, the pipe being inclined for this purpose. The inclination, however, is not sufficient to properly conduct the oil under all conditions, as for instance, when climbing a steep grade the forward end of the motor would be sufficiently elevated as to stop the flow of oil, and it will be apparent under these conditions the flow of oil will stop when the engine is working with a heavy load which is just the time when the oiling system should work most efficiently. In this type of oiling device as there is no forced flow of oil through the conduit, dirt or other sediment is liable to collect therein and greatly retard or stop the flow of oil entirely.

It is, therefore, an object of this invention to provide a more efficient oiling device for this type of motor which will not depend on the force of gravity solely to conduct the oil from the rear to the forward end of the crank case, but will also utilize the centrifugal action of the rotating elements of the magneto to force oil through the conducting conduit.

It is also an object of the invention to provide a device for this purpose which may be mounted on the engine casing in the position occupied by the usual magneto contact so that no machining operations are required in applying this device to the motors already in use.

It is a further object of the invention to provide a device which will be very simple in construction and so will not be easily gotten out of order in operation, and therefore will be very reliable.

With the foregoing and other objects in view, I have devised the construction illustrated in the accompanying drawings, in which—

Fig. 1 is a section through a portion of the top of a motor casing of a Ford engine

immediately above the magneto showing my device applied thereto, a portion of the device being broken away to more clearly show the construction.

Fig. 2 is a top plan view of the device in Fig. 1 removed from the casing.

Fig. 3 is a longitudinal section through the same with the contact element removed.

Fig. 4 is a bottom plan view thereof.

Fig. 5 is a detailed sectional view of the contact element.

Fig. 6 is a top plan view of the body member for a slightly different construction of device for this purpose, removed from the motor.

Fig. 7 is a side elevation thereof.

Fig. 8 is a longitudinal section through this body member showing the insulating oil deflecting plug and contact in position.

Fig. 9 is a side elevation of the body member looking from the right of Fig. 7.

Fig. 10 is a vertical section through the insulating plug and oil deflector.

Fig. 11 is a side elevation looking from the right of Fig. 10.

Fig. 12 is a partial section and partial elevation of still another construction of device.

Fig. 13 is a top plan view of the body member shown in Fig. 12.

Fig. 14 is a side elevation thereof, looking from the right of Fig. 13.

Fig. 15 is a top plan view of an engine in outline showing my device attached thereto, and

Fig. 16 is a detail sectional view through the breather pipe substantially on line 16—16 of Fig. 15 and on an enlarged scale.

Referring to Figs. 1 to 4, the motor casing or housing is indicated at 10 in which are mounted the stationary magnets and coils 11 of the magneto and the rotating permanent magnets 12, which are rotated in the direction of the arrow, and at 13 is shown the magneto contact connected with the coils 11 to conduct the current from these coils. In the top wall of the casing is an opening 14 through which extends the usual magneto contact for connection to the lead-wires from the magneto to the ignition system. In applying my oiling device to a motor its usual magneto contact is removed and my device mounted on the casing in place thereof without the necessity of performing any machining operations whatever.

In the form of my device shown in Figs. 1 to 4, a body member 15 is molded of insulating material which is adapted to be placed on the housing 10 in place of the magneto contact which has been removed, suitable openings 16 being provided for the securing screws 17. This body member is provided with a plug portion 18 projecting through the opening 14 and into the casing to a point adjacent the contact 13, and it is provided on one side thereof with an upright oil deflecting surface 19. I prefer to make this surface substantially flat as shown, though it may, of course, be somewhat concaved if desired, and it faces in a general direction opposed to the direction of rotation of the magnets 12. However, as the plug and contact is not in direct line with the rotating elements 12 but is located to one side thereof as shown in Fig. 15, I find I secure best results if the deflecting surface 19 is not placed at right angles to the plane of rotation of elements 12 but is inclined thereto at an angle of about 30° as shown in Figs. 1 and 15. Thus as the oil is thrown out laterally by the rotating element the deflecting surface 19 faces in a direction substantially opposite to the direction of movement of the oil, and with this arrangement the centrifugal action on the oil gives a greater forced flow through pipe 20. Leading from the body member, preferably in a general direction opposed to the direction of rotation of the magnets 12, is an oil conduit 20 leading to any desired portion of the engine housing, but in the usual construction to a point in the forward portion of the crank case and preferably through the breather pipe 52. For the purpose of connecting this conduit to the insulating body member 15 a nipple 21 is molded in one side of this body preferably threaded at 22 to receive the usual sleeve 23 for attaching the conduit to the nipple. The deflecting surface 19 extends upwardly into the body and is spaced from the side wall thereof to provide a passage 24 leading to the inlet end of the nipple, and at its upper end the surface 19 is curved toward the entrance of this nipple, as shown at 25, so as to direct the oil into this nipple. Extending through the body and the plug portion is an opening 26 for the contact element 27. This element may be of various constructions but in the form shown it comprises a cylindrical body portion having a threaded extension 28 projecting above the top of the body 15 to receive binding nuts 29 for attaching the leadwire 30 and it carries a vertically movable contact 31 which is held in its lowermost position by a spring 32, the element 27 being preferably rolled over as shown at 33 to retain the contact 31 from falling out. The contact 31 is held against the contact 13 when the device is

in position by spring 32, the spring allowing sufficient vertical movement of the contact 31 to compensate for the variations in the distance between the element 13 and the housing which occurs in the manufacture of the motors. Other forms of contacts may be employed, however, if desired. The pipe 20 is secured to the engine by a clip 53 and to facilitate its connection with the breather pipe I insert in this pipe a tube 54 which is somewhat smaller in diameter in its lower portion to fix in the pipe 52. The usual cap 55 is inserted in the top of the tube 54. The oil pipe or conduit 20 is led through the side of the tube 54 and is then curved laterally and terminates at a point adjacent the side of tube 54 as shown in Figs. 15 and 16. I find by this arrangement that the oil is much less liable to be blown out the breather pipe by the flow of air through this pipe under the action of the pistons. The tube 54 may be secured in position by any suitable means such as a wire clip 56 hooked over the bolt 57 at its lower end and the end of the pipe at its upper end as shown at 58. This clip also includes a spring portion 59 to hold the tube tight and allow for various distances from end of tube 54 to bolt 57.

In operation the rotation of the magnets 12 will throw oil against the deflecting surface 19 and the centrifugal action on this oil will cause it to flow up the surface and be deflected thereby into the conduit through which it flows back to the forward end of the casing, or any other position desired. The oil is really forced through this conduit by the coaction of the centrifugal action on the oil and the deflecting surface with the curved portion 25 thereof, so that there is really a forced feed through the conduit which will cause the oil to flow therethrough when going up a grade as well as at other times, and which will also act to prevent sediment gathering in the conduit, so that this device can be depended upon to keep the oil circulating as required. The molded insulation construction is very simple and not likely to be easily gotten out of order.

In the device shown in Figs. 6 to 9, the finished article is practically the same and has the same operation, but instead of making the whole device of molded insulating material I cast the body member 34 of metal, preferably making a die casting, with a nipple 35 leading laterally from one side thereof to which the conduit 20 is connected, and provide the openings 36 for securing screws 17 to attach the device to the motor casing. The body is provided with an opening 37, however, in which is mounted an insulating plug and deflector 38. One side of this plug is provided with an oil deflecting surface 39 corresponding to that 19 of the first form and which is directed in a general

direction opposed to the direction of rotation of the rotating element of the magneto, the same as in the first form. When the plug is placed in the body member this surface is spaced from the sides of opening 37 to form an oil passage 40 leading to the inlet end of the nipple 35, and the upper end of this deflecting surface is curved at 41 the same as in the first form to direct the oil 10 into the nipple. This plug is provided with a longitudinal opening 42 in which is mounted the contact element 27 projecting from the top with the usual binding nuts 29, the conducting stem 28 being insulated from 15 the body 34 by a sleeve 44.

In Figs. 12, 13 and 14, I have shown still another construction for the body or shell 45. In this form it is formed of stamped and drawn metal with a flange 46 having 20 openings 47 for the securing screws 17. Through one side of this shell is an opening 48 to receive a threaded nipple 49 corresponding to the nipple 21 in the first form, this nipple being threaded at 50 to receive 25 the securing sleeve 23 for attaching the conduit 20 to this nipple. The body member is hollow to receive the insulating plug and deflector 38, which is so arranged that its deflecting surface 39 is spaced from the wall 30 of the casing to form an oil passage 51 leading to the inlet for the nipple, and the upper curved portion 49 of this surface is so positioned as to direct the oil into this nipple.

35 The operation is the same in all three of these different constructions, and all three of them are adapted to be secured to the motor casing in place of the usual magneto contact without any machining operations 40 being required. It will be apparent the construction is very simple and will be perfectly reliable in operation as it is not easily gotten out of order.

Having thus set forth the nature of my 45 invention what I claim is:

1. In combination with a motor casing and a rotating element in said casing, of an electric conductor leading from the interior of the casing, a deflector projecting 50 into said casing and provided with an upright deflecting surface forwardly of said conductor facing in a general direction opposed to the direction of rotation of said element, and an oil conducting conduit leading 55 in the general direction toward which said deflecting surface is facing so that the oil does not pass the conductor, the upper end of said deflecting surface being arranged to direct the oil collected by said surface 60 into said conduit.

2. In combination with a motor casing and a rotating element in said casing, of an insulating plug projecting into the casing and cut away on one side to provide a deflecting surface opposed to the general di-

rection of rotation of said element, an electrical contact carried by said plug to the rear of the deflecting surface, and an oil conduit leading in the general direction toward which said deflecting surface is directed, the upper portion of said deflecting surface being arranged to direct oil to said conduit. 70

3. In combination with a motor casing and a rotating element in said casing, a body 75 member of insulating material mounted exteriorly of the casing and provided with a plug portion extending into the casing to a position adjacent the rotating element, said plug portion being cut away at one side 80 to provide a deflecting surface facing in a general direction opposed to the direction of rotation of said element, an oil conduit leading from the side of said body member toward which said deflecting surface faces, 85 the upper portion of said deflecting surface being of a shape to direct oil to said conduit, and an electrical contact element mounted in said member to the rear of said deflecting surface. 90

4. In combination with a motor casing and a rotating element in said casing, a body member of insulating material mounted exteriorly of the casing and provided with a plug portion extending into the casing to 95 a position adjacent the rotating element, said plug portion being cut away at one side to provide a deflecting surface facing in a general direction opposed to the direction of rotation of said element, an oil conduit 100 leading from the side of said body member toward which said deflecting surface is directed, said member being provided with a passage leading to said conduit, one side of said passage being an extension of the deflecting surface and shaped at its top to deflect oil into said conduit, and an electrical contact element mounted in said member to the rear of the deflecting surface. 105

5. In combination with a motor casing 110 and a rotating element in said casing, a body member of molded insulating material mounted on said casing and provided with an extension projecting into said casing beyond the inner surface thereof, a conduit 115 leading from said body member in a general direction opposed to the direction of rotation of said element, said extension being cut away to provide a deflecting surface on one side thereof facing in a general direction opposed to the direction of rotation of said element, said body member being provided with a passage forming a continuation of said surface and inclined at its upper end toward the conduit to direct oil 120 to said conduit, and an electrical contact mounted in said extension to the rear of the deflecting surface. 125

In testimony whereof I affix my signature.
GEORGE A. GAUTHIER.
